E. D. FAHLBERG

SOLDERING FURNACE

Original Filed Sept. 29, 1924

Inventor:
Ernest D. Fahlberg,
By Chindell Parker Parker
Atty.

UNITED STATES PATENT OFFICE.

ERNEST DAVID FAHLBERG, OF MADISON, WISCONSIN, ASSIGNOR TO E. D. FAHLBERG MFG. COMPANY, OF MADISON, WISCONSIN, A CORPORATION OF WISCONSIN.

SOLDERING FURNACE.

Application filed September 29, 1924, Serial No. 740,462. Renewed January 21, 1928.

The invention relates to improvements in soldering furnaces, and more particularly to such furnaces of the portable type. The primary object of my invention is to provide a new and improved soldering furnace which is adapted to form part of a complete soldering kit or outfit particularly suitable for use in the home or on an automobile, and which more specifically is provided with compartments adapted to receive the essential soldering accessories.

Another object is to provide novel means for extinguishing the flame and enclosing the burners to prevent leakage and evaporation. A further object is to provide a portable soldering furnace which is simple and compact in construction, inexpensive and easy to manufacture, and having an exceptionally low fire hazard. Other objects and advantages will become apparent as the description proceeds.

In the drawings, Figure 1 is a perspective view, with parts broken away, of a furnace constructed in accordance with my invention.

Fig. 2 is a longitudinal section taken along line 2—2 of Fig. 3. Fig. 3 is a transverse section taken along line 3—3 of Fig. 2. While my invention is susceptible of various modifications and alternative constructions, I have shown in the drawings and will herein describe in detail the preferred embodiment, but it is to be understood that I do not thereby intend to limit the invention to the particular form disclosed but aim in the appended claims to cover all modifications and alternative constructions falling within the spirit and scope of the invention.

Referring to the exemplary embodiment illustrated in the drawings, 10 represents the body of the furnace which preferably consists of a rectangular box open at the top and at one end, and 11 designates a suitable cover adapted to completely close the box. In the cover 11, as shown, the edges are bent down to provide a flange 12 adapted to fit over the upper edges of the box 10, and one end is formed with a depending plate 13 for closing the open end of said box. The plate 13, when the cover 11 is in position, fits in

side of two vertical flanges 14 formed by bending the front edges of the side walls of the box 10 inwardly.

The bottom of the box 10 is closed by a hollow rectangular base 15 which is adapted to serve as a reservoir for the fuel, such as denatured alcohol. In the present instance, the base 15 is constructed of a lower section 16 to which the walls of the box 10 are soldered, and an upper section 17 telescoping into the lower section and soldered thereto to obtain a tight joint. A flanged filling opening 18 is formed in the front end of the section 17, and is normally closed by a cork 19.

Mounted on the base 15 within the closed end of the box 10 is a burner which preferably comprises a tube 20 secured to the section 17, and a suitable wick 21 extending through the tube into the fuel. When the furnace is not in use, a tubular cap 22 is adapted to telescope with the tube 20 to close the latter. The cap 22 acts as a flame extinguisher, and prevents leakage and evaporation of the fuel.

Removably mounted in the box 10 and substantially coextensive in length therewith is a tool support 23 which is constructed of a piece of metal having its sides bent down and then inwardly to constitute legs 24. The legs 24 are of such height that the top of the support is near the top of the box 10, and the space below forms a compartment sufficient in size to receive various soldering accessories, such as the boxes 25 for the flux and sal ammoniac. At its rear end, the support 23 is formed with a rectangular opening 26 directly over the burner tube 20 to expose the element to be heated to the flame. This element is herein shown as a soldering iron having a head 27 and a telescoping handle 28. The sides 29 of the opening 26 are bent upwardly and inwardly to form a burner hood which serves to protect the flame and to direct and confine it to the head 27. When not in use, the soldering iron can be telescoped and positioned at one side of the hood as shown in Figs. 2 and 3.

It will be evident that I have provided a handy soldering furnace which can be advantageously used in the home, the automobile, and other places for light jobs, such as

soldering electrical connections and radio equipment, or repairing utensils and the like. The furnace is small and compact, and can be carried with the necessary soldering accessories in the pocket or tool kit to be set up and used where needed, thereby providing an efficient self contained soldering outfit.

I claim as my invention:

- 10 1. A soldering furnace having, in combination, a body open at the top and front, and closed at the bottom by an integral fuel container, a filling opening in the front end of said container, a wick burner in the form 15 of a tube on the other end of said container, a combined tool holder and burner hood movably mounted in said body over said container, a flame extinguisher adapted to telescope with said burner, and a cover having 20 a depending plate at its front end, said cover being adapted to close said body.
2. A soldering furnace having, in combination, a body closed at the bottom by an integral fuel container, a burner on one end 25 of said container, and a tool holder removably mounted in said body, said tool holder consisting of a piece of metal having bent down sides constituting legs and being formed with a hole directly over said burner, 30 and flanges on two opposite sides of said hole extending upwardly and toward each other to constitute a hood.
3. A soldering furnace having, in combination, a body in the form of a box, a fuel 35 container forming the bottom of said box, a burner on said container, a removable tool holder and burner hood in said box, and means for closing said box.
4. A soldering furnace having, in combination, a rectangular body open at the top 40 and front and closed at the bottom by a fuel container, a cover for closing said top and front, a burner on said fuel reservoir,

and a hood having inclined sides over said burner.

5. A soldering furnace having, in combination a rectangular box, a fuel container in the bottom of said box, a filling opening in one end of said container, a burner on the other end of said container, a combined 50 hood and tool support removably mounted in said box on said container with the hood positioned over said burner, and a removable cover for closing said box.

6. A soldering furnace comprising, in combination, a box, a fuel reservoir in the bottom of said box, a tube burner on one end of said reservoir provided with a wick, and a tubular cap telescoping over said burner tube, said cap serving as a fire extinguisher and to prevent leakage and evaporation of fuel.

7. A soldering furnace comprising, in combination, a box having a fuel reservoir in the bottom thereof, a burner on said fuel reservoir, a tool holder removably mounted in said box, said holder defining a compartment for receiving various soldering accessories, a hood over said burner, and a cover for closing said box.

8. A soldering furnace having, in combination, a box open at the front and top, and containing a fuel reservoir at the bottom thereof, a filling opening at the front end of said reservoir, a burner on the other end of said reservoir, a combined tool holder and hood in said box with the hood positioned over said burner, said last element defining a compartment over said reservoir for receiving various soldering accessories and constituting a shaft for supporting a soldering iron when not in use, and a cover for completely closing said box.

In testimony whereof, I have hereunto affixed my signature.

ERNEST DAVID FAHLBERG.
